ADJUSTABLE COLLAR FOR RESUSCITATORS AND RESPIRATORS

John E. Lindley, Houston, Tex., and Ancil L. Lindley, Macon, Miss.

Application November 28, 1955, Serial No. 549,351

8 Claims. (Cl. 128—30)

This invention relates to an adjustable collar for use in resuscitators and respirators.

The collar construction disclosed herein is particularly adapted for use on a resuscitator such as disclosed in our copending application Serial No. 532,866, filed on September 7, 1955, but it is to be understood that our novel and improved collar is adapted for use in any respirator or resuscitator wherein the body or head of a patient, or both, is enclosed in a pressure chamber.

In all resuscitators or respirators, such as the widely known iron lung, one of the major problems has been the development of a collar which will seal at the neck of the patient without undue constrictions or harmful or uncomfortable irritation. It must be sanitary, easily and quickly applied and removed, be capable of complete replacement with simplicity and ease when it becomes necessary, be adaptable to widely varying neck sizes, and must permit the skin of the patient at the neck to breathe.

In prior collar structures use has been made of a sponge rubber neck ring, and also a spiral twist neck collar, the latter type being illustrated in detail in our copending application, Serial No. 532,866. In the case of the sponge rubber collars an aperture was formed in the sheet of sponge and the head of the patient inserted therethrough, stretching the rubber, the resilience causing it to then grip the neck. It was necessary to size the opening and thus the collar to the patient, since while there was some adjustability in the rubber, the margin was very small. It was found that a rather small inaccuracy made the collar too tight for comfort or too loose for a proper seal. Further, the sponge sheet was fragile and slow and difficult to apply.

An attempt was made to cut the collar from the aperture to one edge, and then seal the cut with a tape. It was still necessary to size the collar to the patient, and the application to the patient still proved to be a slow and cumbersome procedure.

An object of the invention is to provide a collar which will provide an efficient air tight seal around the neck of patients in resuscitators or respirators where different pressures of gases, either positive or negative, are desired to be placed on either the head or body of the patient.

A further object is to provide a sponge rubber collar which can be applied with great rapidity in an accurate snug fit regardless of the neck size of the patient.

Still another object of the invention is to provide a collar of a soft, non-traumatizing and non-irritating elastic material that can form an air-tight seal against the patient's neck without damaging the skin or interfering with the circulation of blood in the patient's neck area.

Another object of the invention is to provide a collar than can be applied with ease and rapidity, making it especially useful in the case of apnea of a new born infant.

A further object of the invention is to provide a collar which can be easily replaced as a unit, or can be easily disassembled for cleaning.

Still another object of the invention is to provide a sponge rubber collar wherein the area that is axially mov-

2

able is relatively small, thereby reducing the amount of friction on the patient's neck, and making rapid changes of pressure on either side of the collar more easily accomplished.

5 Another object of the invention is to form a collar wherein changes of pressure on either side do not produce increased pressure of the collar against the patient's neck.

A further object of the invention is to provide a collar which has a permanent split between the aperture and 10 one side edge, permitting a resuscitator or respirator construction which will open midway in a horizontal plane, thus allowing easier initial placement of the patient and greater accessibility for examination and treatment.

A final object of the invention is to provide a collar 15 which meets all basic requirements and is at the same time durable and inexpensive to manufacture.

With the above and other objects in view as will be presently apparent, the invention consists in general of certain novel details of construction and combinations of 20 parts hereinafter fully described, illustrated in the accompanying drawings and particularly claimed.

In the accompanying drawings like characters of reference denote like parts in the several views, and

Fig. 1 is a fragmentary longitudinal section taken on the 25 line 1—1 of Fig. 2, showing a resuscitator with the collar construction of the present invention applied to the partition between head and body compartments; and

Fig. 2 is a cross-sectional view taken on the line 2—2 of Fig. 1, and showing the collar construction in front elevation.

The resuscitator structure illustrated in the drawings does not form a part of this application and is therefore shown in simplified form for greater clarity. The invention resides in the sealing collar and its related parts 35 which will be hereinafter fully described.

In the present disclosure the collar is shown as applied to an infant resuscitator. The resuscitator comprises an elongated pressure chamber which is divided by the partition 10 into a head compartment 11 and body compartment 12. The partition 10 is divided into a rectangular lower plate 13 and an arcuate upper plate 14. A cover 15 which is arcuate in transverse cross-section is hinged to the pressure chamber and covers both compartments. A seal 16 is provided for the edges of the 40 cover and a resilient strip 17 seals the meeting edges of the cover and the resilient strip 17 seals the meeting edges of the partition plates 13 and 14.

An arcuate notch 18 in the lower plate 13 and a similar arcuate notch 19 in the upper plate 14 provide a relatively large neck opening when the cover is closed. It 50 will be noted that the upper plate 14 is secured to the cover. While the present illustration, therefore, shows the collar structure as applied to a split partition, it can be equally well applied to a unitary partition or wall, such as occurs in many respirators.

55 A floor partition 20 supports the body of the patient and the resilient block 21 supports the head. The head compartment is provided with a hinged door 41 which opens outwardly to give full access to the collar structure when the cover 15 is closed.

60 The basic element of the collar structure of the present invention is the sponge rubber sheet 22. This sheet has a generally curved marginal edge which conforms somewhat to the shape of the partition 10. The sheet 22 is provided with a neck aperture 23, and a cut is made 65 through the sheet extending from the aperture 23 to the marginal edge, the cut forming two free ends 24 and 25 which are made to overlap to any degree necessary to obtain a properly sized neck opening.

A bar is bent to form a horseshoe shaped clamping member 26, which has an arcuate upper portion 27 and depending legs 28a and 28b. To provide sockets for the ends of said legs eyes 29 are screwed into the rectangular

lower plate 13 adjacent the lower edge thereof. Each of said legs 28a and 28b is provided with a transversely projecting stud 30 which serves as a stop to limit the downward movement of the legs within the eyes 29.

Above the arcuate upper portion 27 of the clamping member 26, there is placed an L-shaped latch 31. The latch has a threaded end 32 which is engaged with a cooperatively threaded aperture 33 that is drilled and tapped into the plate 14. The opposite end of the latch 31 is bent outwardly to form a shoulder 34 and then bent inwardly upon itself to form a hook end 35. The cooperating threads of the end 32 and aperture 33 cause the latch 31 to move inwardly as it is turned down into latching position.

To support and clamp the sponge rubber sheet 22 at the points between the legs 28 there is provided an arcuate plate 36. Bolts 37 with wing nuts 38 secure the plate 36 to the lower plate 13 and the sponge rubber sheet is clamped between said plates. The purpose of the separate plate 36 is to support the lower portion of the sponge rubber sheet when the clamping member 27 is removed. This prevents complete collapse and disengagement of the collar and is important where speed is critical in asphyxia cases. It will be understood that if desired the plate 36 could have its ends secured to the legs of the clamping member 26, forming a simplified structure, but without the advantage just described.

In order to secure a tight gas seal between the overlapping ends 24 and 25, a flat projection 39 extends radially from the edge of the arcuate notch 18 at a point behind the overlapping ends. This is shown as an eye but may be any suitable flat projection which is rounded to reduce danger of injury to the patient. In overlying clamping relation with the flat projection 39 is a plate 40 which extends from the leg 28b to the arcuate upper portion 27. This is preferably attached to the inner face of the clamping member 26, so that a slightly greater pressure will be applied to the overlapping ends 24 and 25 than will be applied to the other parts of the sponge rubber sheet by the clamping member 26.

The operation of the novel collar structure is as follows:

It is assumed that the resuscitator cover is open, the collar structure being disassembled, with the lower portion held by the plate 36, the upper portion falling limply and the ends 24 and 25 being free. The patient is inserted into the pressure chamber with the body on the floor partition 29 and the head on the block 21. The cover 15 is closed and clamped. The sponge rubber sheet 22 is then adjusted around the neck of the patient and the ends 24 and 25 overlapped to provide an opening of the exact size desired. The legs 28a and 28b of the horseshoe-shaped clamping member 26 are then inserted in the eyes 29, the studs 30 limiting the movement therein. The member 26 is then pivoted inwardly and pressed against the sponge rubber sheet. After that the latch 31 is pivoted downwardly, moving inwardly because of the threaded end 32, the shoulder 34 pressing downwardly on the arcuate upper portion 27 of the clamping member and the hook end 35 forcing the clamping member inwardly. The plate 40 presses the ends 24 and 25 strongly against the projection 39. A complete seal is effected, therefore, at all points, the whole operation requiring a minimum amount of time.

While there is herein shown and described the preferred embodiments of the invention, it is nevertheless to be understood that minor changes may be made therein without departing from the spirit and scope of the invention as claimed.

What is claimed is:

1. In an adjustable collar for resuscitators and respirators having a planar wall and a neck aperture formed therein, a sheet of resilient sealing material positioned against said walls, said sheet having a neck-receiving aperture formed therein and a cut therethrough extending

from the edge of said aperture to the edge of said sheet forming two free ends adapted to be overlapped for adjustment of said neck aperture, clamping means supported by said wall and adapted to surround said aperture and press against said sheet to maintain a sealing relation between said sheet and wall, and additional clamping means supported by said first clamping means and pressing against said overlapped ends for maintaining a sealing relation therebetween.

2. In an adjustable collar for resuscitators and respirators having a planar wall and a neck aperture formed therein, a sheet of resilient sealing material positioned against said wall, said sheet having a neck-receiving aperture formed therein and a cut therethrough extending from the edge of said aperture to the edge of said sheet forming two free ends adapted to be overlapped for adjustment of said neck aperture, releasable clamping means surrounding said aperture and pressing against said sheet to maintain a sealing relation between said sheet and wall, additional clamping means supported by said first clamping means and pressing against said overlapped ends for maintaining a sealing relation therebetween, and latch means releasably holding said clamping means in clamping position.

3. In a collar for resuscitators and respirators having a planar wall and a neck aperture formed therein, a sheet of resilient sealing material positioned against said wall, said sheet having a neck-receiving aperture formed therein and a cut therethrough extending from the edge of said aperture to the edge of said sheet forming two free ends adapted to be overlapped for adjustment of said neck aperture, a horseshoe-shaped clamping element pressing against said sheet, a second clamping element extending between the legs of said horseshoe-shaped clamping element and pressing against said sheet, and means supported by said horseshoe-shaped clamping element and pressing against said overlapping ends to maintain a sealing relation therebetween.

4. In a collar for resuscitators and respirators having a planar wall and a neck aperture formed therein, a sheet of resilient sealing material positioned against said wall, said sheet having a neck-receiving aperture formed therein and a cut therethrough extending from the edge of said aperture to the edge of said sheet forming two free ends adapted to be overlapped for adjustment of said neck aperture, a horseshoe-shaped clamping element pressing against said sheet, a second clamping element extending between the legs of said horseshoe-shaped clamping element and pressing against said sheet, socket means receiving the free ends of said legs, releasable latch means engaging the horseshoe-shaped clamping element and holding it in clamping position, and means supported by said horseshoe-shaped clamping element pressing against said overlapping ends to retain a sealing relation therebetween.

5. In a collar for resuscitators and respirators having a planar wall and a neck aperture formed therein, a sheet of resilient sealing material positioned against said wall, said sheet having a neck receiving aperture formed therein and a cut therethrough extending from the edge of said aperture to the edge of said sheet forming two free ends adapted to be overlapped for adjustment of said neck aperture, clamping means surrounding said wall aperture and pressing against said sheet, a projection extending from said wall aperture radially thereof and positioned behind said overlapping free ends, and auxiliary clamping means supported by said clamping means and positioned to overlie said projection, whereby said overlapping ends will be clamped between said projection and said plate to effect a seal.

6. In a collar for resuscitators and respirators having a planar wall and a neck-receiving aperture formed therein, a sheet of resilient sealing material positioned against said wall, said sheet having a neck-receiving aperture

formed therein and a cut therethrough extending from the edge of said aperture to the edge of said sheet forming two free ends adapted to be overlapped for adjustment of said neck aperture, a horseshoe-shaped clamping member pressing against said sheet, a clamping plate secured to said wall and extending between the legs of said horseshoe-shaped clamping member, a flat projection extending from said wall aperture radially thereof and positioned behind said overlapping free ends, and plate means supported by said horseshoe-shaped clamping member and positioned to overlie said flat projection, whereby said overlapping ends will be clamped between said projection and said plate to effect a seal.

7. In a collar for resuscitators and respirators having a planar wall and a neck-receiving aperture formed therein, a sheet of resilient sealing material positioned against said wall, said sheet having a neck-receiving aperture formed therein and a cut therethrough extending from the edge of said aperture to the edge of said sheet forming two free ends adapted to be overlapped for adjustment of said neck aperture, a horseshoe-shaped clamping member pressing against said sheet, a clamping plate secured to said wall and extending between the

legs of said horseshoe-shaped clamping member, socket means receiving the ends of said legs, a latch member engaging the closed end of said clamping member and pressing said member downwardly into said sockets and inwardly against said sheet, a flat projection extending from said wall aperture radially thereof and positioned behind said overlapping free ends, and plate means supported by said horseshoe-shaped clamping member and positioned to overlie said flat projection, whereby said overlapping ends will be clamped between said projection and said plate to effect a seal.

5 8. A structure as set forth in claim 7, wherein said latch is L-shaped, one end thereof being threadedly engaged with said wall, the other end being offset outwardly and downwardly defining a shoulder engaging the end of said clamping member and a projection engaging the side face of said clamping member.
